(57) **CLAIM**

The ornamental design for a watch strap, as shown and described.

DESCRIPTION

FIG. 1 is a top, front and right side perspective view of a watch strap showing my new design;

FIG. 2 is a perspective view thereof, in a state of use;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view thereof, taken from the encircled portion 9 in FIG. 1; and,

FIG. 10 is an enlarged view thereof, taken from the encircled portion 10 in FIG. 1.

The broken lines in the drawings represent portions of the watch strap and form no part of the claimed design. The other broken lines represent text indicia and form no part of the claimed design. The dot-dash lines in FIGS. 1, 9, and 10 are included to show a partially enlarged view only and form no part of the claimed design.
